ESTERS OF 19-NORTESTOSTERONE

Erik Duyvené De Wit, Oss, and Gerhard Anthony Overbeek, Nijmegen, Netherlands, assignors to Organon Inc., West Orange, N.J., a corporation of New Jersey
No Drawing. Filed Feb. 2, 1959, Ser. No. 790,357
Claims priority, application Netherlands Feb. 25, 1958
4 Claims. (Cl. 260—397.4)

The present invention pertains to new esters of 19-nor-testosterone.

It is known that testosterone and esters thereof have an anabolic effect in addition to an androgenic effect. Owing to their anabolic activity these compounds have been applied for example in the treatment of cancer of the breast, in which, however, the virilizing effect is most undesirable. One has therefore long been seeking for compounds that do have an anabolic but only a slight virilizing effect.

Esters of 19-nortestosterone are described, the anabolic and androgenic activity of which are very favourably related. These are the esters of 19-nortestosterone and aliphatic or cyclo-aliphatic-aliphatic carboxylic acids with two to eight carbon atoms or aromatic-aliphatic carboxylic acids, of which the aliphatic part contains 2 or 3 carbon atoms.

Of these known esters of 19-nortestosterone the β -phenylpropionate has so far proved to be the most useful, because in this compound the relation between anabolic and androgenic activity is the most favourable. Consequently this compound is applied in a very large number of cases, of which may be mentioned by way of example cancer of the breast, osteoporosis, decubitus, retarded growth, asthenia, osteogenesis imperfecta and for which further reference may be made to the very extensive medical literature on this compound.

Although in most of the cases excellent results are obtained with this known compound, the need remains for anabolically acting compounds having a more prolonged effect than the 19-nortestosterone β -phenylpropionate (hereinafter indicated by nor-TPP). In addition one is searching for compounds in which the relation between the anabolic and the androgenic effect is even more favourable than in the nor-TPP.

It is an object of this invention to provide new esters of 19-nortestosterone the relation of the anabolic and the androgenic effect of which is more favourable than in the nor-TPP and which have a duration of action which is substantially longer than that of the nor-TPP.

Treatment	Effect after 2 weeks			Effect after 4 weeks			Effect after 6 weeks		
	AMLA	ASV	AMLA/ASV	AMLA	ASV	AMLA/ASV	AMLA	ASV	AMLA/ASV
nor-TPP	21.4	9.7	2.2	5.3	5.4	—	7.0	7.1	—
19-nortest. undecylenate	26.4	5.0	5.3	38.6	5.0	7.7	32.1	6.5	5.0
19-nortest. octeno carboxylate	27.2	5.9	4.6	36.2	5.4	6.7	24.3	4.8	5.1
19-nortest. dodeceno carboxylate	22.8	6.0	3.8	30.3	5.1	5.9	28.6	3.2	9.0
19-nortest. tetradeceno carboxylate	22.6	4.6	4.9	22.4	4.2	5.3	20.1	3.7	5.4
19-nortest. oleate	16.8	3.5	4.8	24.2	4.0	6.0	25.7	4.1	6.3
19-nortest. decanoate	25.0	2.7	9.2	62.7	5.5	11.4	50	6.8	7.3
19-nortest. laurate	23.2	2.7	8.6	70	5.8	12	58	6.9	8.4
19-nortest. myristate	19.4	2.2	8.8	42	4.2	10	43.7	4.1	10.7
19-nortest. palmitate	7.5	1.4	5.4	27.5	1.9	15	38.2	2.2	17.3

2

The compounds according to the invention are 17-esters of 19-nortestosterone and saturated and unsaturated aliphatic carboxylic acids having 9-18 carbon atoms.

These compounds can be prepared by converting 5 19-nortestosterone into said esters in a manner known per se for ester formation, for example by reacting 19-nortestosterone dissolved in a suitable solvent with the acid chloride of the desired acid or with the anhydride of said acid.

10 The testing of the effect of compounds on the relation between anabolic and androgenic activity is mostly carried out by means of tests on castrated rats, in which some time after the administration of the compound to be tested the weights of the *musculus levator ani* and 15 of the seminal vesicles is determined.

At the same time the weights of these organs are determined of rats of the same age to which the compound in question has not been administered but which have been treated further in quite the same manner.

20 The difference in weight of the *musculi levator ani* (Δ MLA) then is a measure for the anabolic and that of the seminal vesicles (Δ SV) for the androgenic activity. So the relation Δ MLA/ Δ SP is a measure for the relation between anabolic and androgenic activity.

25 With substances which are destined for clinical application it is desirable that this relation is as great as possible. This relation should not only be favourable at a certain time after administration, but should maintain this favourable value as long as the substance in question still exerts some effect. So it may not be such that after injection the substance has a good anabolic effect and a slight virilizing effect, while this would be the other way about after for example a week.

30 So the above test in which Δ MLA/ Δ SV is determined, is very suitable for testing anabolic compounds, because it has appeared that there is a very good correlation between the effect of the substances in this test and on clinical application.

35 The present compounds have been tested according to the above method and compared with the compound so far known to be the compound having the most favourable relation between anabolic and androgenic effect, viz. the nor-TPP.

40 The following results were obtained (each figure is the result of an experiment performed with 8 rats weighing about 50 grams when the experiment started).

45 The treatment consists of a single administration of 50 1 mg. of the compound in question.

It follows from this table that after 4 weeks the effect of the nor-TPP has ceased practically entirely.

As with this compound Δ MLA is only very slight after the said period of time, the statement of the value of Δ MLA/ Δ SV has no purpose here (theoretically both Δ SV and Δ MLA would have to be nil if there is no effect at all). It also appears from the table that the present compounds do not only have a larger protein-saving effect but also a slighter androgenic effect, while even after 6 weeks a pronounced effect is present.

That is the present compounds the relation between the anabolic and the androgenic effect would be so favourable could by no means be anticipated, because it is known that on esterification of testosterone with some of the acids in question the androgenic effect increases very strongly. It was not to be expected that with nor-testosterone the very anabolic effect and not the androgenic effect should be amplified to such a large extent.

The present compounds do not only have favourable effects in the animal experiment, but also on clinical application. It has appeared for example in nitrogen balance experiments in men that in a certain case the protein-saving effect of the nor-TPP which is applied on a very large scale amounted to about 15 g. daily during the first 15 days after injection, whereas this with for example the nortestosterone undecylenate and -decanoate amounted to about 25 g. daily after administration of an equal dose. This larger effect, added to the much more prolonged effect renders the present compounds very valuable for clinical application.

The initial effect of the 19-nortestosterone oleate and -palmitate is somewhat smaller than that of the other compounds; against this is the more prolonged effect, as a result of which this compound becomes of great importance for veterinary application, because for example by a single injection in young pigs the protein formation can be promoted to a very great extent at the expense of the deposit of fat, as a result of which an improved meat is obtained in a shorter time. Any unpleasant taste of the meat, as is the case after injection of androgenic substances, need not be feared, because the androgenic effect of these compounds is negligible.

In addition to the acids with one double bond also acids with more than one double bond may be considered for the present process, as well as acids with a triple bond.

In the process according to the invention start is preferably made from the acid chloride of the acid in question.

The following examples illustrate the process.

Example I

(a) 1 g. of 19-nortestosterone is dissolved in 3 ml. of dry pyridine, after which the resulting solution is cooled to -20° C. A solution of 1. g. of undecylenic acid chloride in 3 ml. of dry benzene is added to the cooled solution. The mixture is maintained at -15° C. for 16 hours and then poured into ice water. The aqueous liquid is extracted with benzene, the benzene solution is washed with resp. 1 N sodium hydroxide solution, 2 N hydrochloric acid and with water till neutral reaction.

Then the solution is dried on sodium sulphate, filtered, and evaporated to dryness. The residue, 1.63 g. is dissolved in hexane, this solution is filtered over 30 g. of neutral aluminium oxide, and evaporated to dryness. On paper chromatographic investigation it turned out that the obtained 19-nortestosterone 17-undecylenate which at room temperature is an oil consists of a single compound. $[\alpha]_D = +39.6^\circ$ (in chloroform). $E_{239\mu} = 15,600$ (in ethanol).

10 (b) In the same manner as mentioned sub (a) the octene carboxylic ester of 19-nortestosterone is prepared in a yield of 88%. $E_{239\mu} = 15,900$ (in ethanol).

(c) In the same manner as mentioned sub (a) the dodecene carboxylic ester of 19-nortestosterone is prepared in a yield of 83%. $E_{239\mu} = 16,200$ (in ethanol).

(d) In the same manner as mentioned sub (a) the tetradecene carboxylic ester of 19-nortestosterone is prepared in a yield of 80%. $E_{239\mu} = 15,600$ (in ethanol).

(e) In the same manner as mentioned sub (a) the 20 oleate of 19-nortestosterone is prepared in a yield of 87%. $E_{239\mu} = 15,400$ (in ethanol).

(f) In the same manner as mentioned sub (a) the 25 decanoate of 19-nortestosterone is prepared in a nearly quantitative yield. The ester is an oil at room temperature. $E_{239\mu} = 16,000$ (in ethanol).

(g) In the same manner as mentioned sub (a) the 30 myristate of 19-nortestosterone is prepared in a yield of 95%. $E_{239\mu} = 15,900$ (in ethanol).

(h) In the same manner as mentioned sub (a) the 35 palmitate of 19-nortestosterone is prepared in a yield of 90%. $[\alpha]_D = +32.9^\circ$ (in chloroform), $E_{239\mu} = 15,300$ (in ethanol), M.P. 53-56° C.

Example II

35 1 g. of 19-nortestosterone and 2 g. of lauric anhydride are dissolved in 20 ml. of dry pyridine. The mixture is refluxed for 4 hours. Then 2 ml. of water are added and refluxing is continued for some more hours in order to decompose the excess of anhydride. Then the mixture is evaporated to dryness, the residue is taken up in benzene, after which this benzene solution is treated in the manner of Example I. In this manner the 19-nortestosterone-17-laurate is obtained in a 85% yield. $[\alpha]_D = +37.4^\circ$ (in chloroform); $E_{239\mu} = 15,900$; M.P. 45-46° C.

45 What we claim is:

1. 19-nortestosterone 17-esters of saturated straight chain aliphatic carboxylic acids containing from 10 to 14 carbon atoms.
2. 19-nortestosterone 17-decanoate.
3. 19-nortestosterone 17-laurate.
4. 19-nortestosterone 17-myristate.
